DETACHABLE VENTILATING SHADE BRACKET

Filed July 10, 1922

Inventor:

George Anderson
By Jason, Fenwick & Lawrence,
Agents.

UNITED STATES PATENT OFFICE.

GEORGE ANDERSON, OF CHICAGO, ILLINOIS.

DETACHABLE VENTILATING-SHADE BRACKET.

Application filed July 10, 1922. Serial No. 573,778.

To all whom it may concern:

Be it known that I, GEORGE ANDERSON, a citizen of the United States, residing at Chicago, in the county of Cook and State 5 of Illinois, have invented certain new and useful Improvements in Detachable Ventilating-Shade Brackets; and I do hereby declare the following to be a full, clear, and exact description of the invention, such as 10 will enable others skilled in the art to which it appertains to make and use the same.

This invention relates to improvements in shade brackets or the like and has for its particular object the provision of a bracket 15 for maintaining a window shade in position so that the same may be moved up and down with the window to provide for proper and convenient ventilation above the window when the same is lowered.

Another object of this invention is the provision of a bracket for supporting window shades or the like which shall be mounted directly upon the upper or rearward window and which will not interfere with 20 the motion of one window past the other when it is desired to clean the windows or for any other operation which necessitates the movement of the sashes up and down past each other.

A further important object of this invention is the provision of a two part bracket 25 for window shades or the like which is adapted to have one of its parts readily removed from a window so that the window 30 pane may be readily cleaned and so that there will be no obstruction to the movement of one of the sashes past the other.

Still another important object of this invention is the provision of a two-part detachable shade bracket for windows which shall be adapted to maintain the shade on its roller in a position upon the upper window sash so that it may be movable with the window and which, when applied, shall 40 automatically assume a position whereby the roller for the shade is securely maintained in place.

Another and further important object of 45 this invention is the provision of a shade bracket which shall have a slotted seat at the outer end of one of the bracket members thereof adapted to readily receive and securely maintain in position the spring-operating pin on the end of the roller.

Other and further important objects of 55 the invention will be apparent from the disclosures in the accompanying drawings and following specification.

The invention, in a preferred form, is 60 illustrated in the drawings and hereinafter 65 more fully described.

In the drawings:

Fig. 1 is a plan view of a pair of cooperating window sashes in a window frame showing the improved bracket of this invention applied thereto;

Fig. 2 is a sectional view taken on line 2—2 of Fig. 1 looking in a direction indicated by the arrows;

Fig. 3 is a front plan view of the sash 70 plate of this invention;

Fig. 4 is a sectional view taken on the line 4—4 of Fig. 3;

Fig. 5 is a perspective view showing the improved removable bracket of the invention;

Fig. 6 is a detail view showing the construction of the slotted bracket, and

Figure 7 is a front elevation view on an enlarged scale of the bracket plate with the 80 bracket mounted in said plate.

As shown in the drawings, the reference numeral 10 indicates a window sash and, as shown, is applied to the rear or upper window sash as commonly used in window construction. A lower or forward sash is 85 shown at 12 and is adapted to slide over a rear sash 10 as in the common window construction.

As shown in the drawings the improved 90 detachable shade bracket of the invention is applied directly to the face of the sash 10. The bracket is made in two parts, one part consisting of a plate 14 adapted to be fixed to the window sash 10 and held in predetermined position thereon by means of ordinary wood screws 14' or the like. The plate 14 is provided at its top and bottom with bent over lugs or ears 16 which provide a pair of slots into which is adapted to ride 100 a corresponding plate 18 which forms an integral part of the detachable bracket member 20 and the corresponding member for the other side of the window sash 22. As shown in Fig. 5, an opening or slot 24 is 105 provided in the brackets 20 and 22 which extends into the plate 18 of each of the brackets and also extends into the bracket

member proper, as 20 or 22, which is positioned at right angles to the plate 18 and integral therewith. The purpose of the slot 24 is to allow the bracket member 20 to ride over the heads of the screws 14' which are used for fixing the plate 14 in position on the sash 10. As will be noted, the slot 24 does not extend completely through the plate 18 and, when the bracket 20 is applied 10 to the fixed plate member 14 with the edges thereof sliding under the lugs 16, its position will be automatically determined by the contact of the forward end of the slot 24 with one of the screws fixing the plate 14 in position. After the shade roller is then applied to the brackets there is no possibility of the roller becoming detached or falling off in use as the pressure against the brackets 20 and 22 acts only in the direction to force the rear end of the slot 24 more firmly against the wood screws which maintain the plate 14 in position.

As shown at 24^a in both Figs. 5 and 6, a slight indentation is made in the bracket members 20 and 22 which eliminates any possibility of friction between the edges of the shade and the face of the bracket when the shade is rolled up or down upon the rollers. Such friction occurs in the ordinary bracket as usually the shade does not track exactly upon the roller and runs either to one side or the other which results in impaired and sometimes discontinued operation.

It will be seen that herein is provided a device which will provide effectively for ventilation of rooms and at the same time afford proper privacy by means of shades which can be drawn down as far as desired but left open at the top. The length of the brackets 20 and 22 is such that the shade will pass directly over the face of the outer or lower window 12 without contacting therewith, and it is evident that there will be absolutely no conflict between the window sashes 10 and 12 except when it is desired to move the outer sash 12 up past the sash 10 and this can be accomplished by simply removing the shade roller and the brackets 20 and 22 which readily slide out of the grooves in the plate 14. The windows can then be manipulated as desired for purposes of cleaning and the like and when such operation is finished the shade 55 can be replaced with a minimum expenditure of time and energy particularly on account of the fact that the brackets 20 and 22 will automatically position themselves in the plate 14 by means of the abutment of 60 the end of the slot 24 against the heads of the attaching screws for the plate.

I am aware that many changes may be made and numerous details of construction varied throughout a wide range without departing from the principles of this inven-

tion and I therefore do not purpose limiting the patent granted hereon otherwise than as necessitated by the prior art.

I claim as my invention:

1. A shade bracket comprising a plate 70 having inwardly extending lugs at the top and bottom forming grooves, the plate being provided with spaced openings for receiving fastening means, and a bracket member including a plate having a base portion at right angles thereto provided with an elongated longitudinal slot with one end spaced from the forward end of the base, and the other end extending partially into the bracket member proper to clear the head 75 of a fastening of the first-named plate, and the other end of the slot adapted to engage the head of the fastening when the base is slid into the grooves formed by the lugs, to limit the outward displacement of the 80 bracket member.

2. A detachable ventilating shade bracket comprising a plate adapted to be attached to a window-sash, and having overturned inwardly extending lugs on the top and bottom forming grooves, said plate being provided with spaced openings adapted to receive fastening screws with the heads thereof projecting from the surface of the plate, a bracket member having a base portion at 90 right angles thereto adapted to be slid into said grooves from the inside and provided with a central elongated slot extending horizontally from a point in spaced relation to the inner end of the base to and into the 100 bracket portion, to clear the head of a fastening screw, the other end of the slot being adapted to engage the head of the fastening screw last-mentioned to form a stop for the bracket and limit the outward movement 105 thereof.

3. A detachable ventilating shade bracket comprising a plate adapted to be attached to the top of the upper window-sash, having overturned inwardly extending lugs on the 110 top and bottom edges forming grooves, said plate being provided with spaced openings, at least one of which is designed to receive a headed fastening member with the head 115 projecting from the surface of the plate, and a bracket member comprising a main portion having a portion in angular relation thereto adapted to slidably fit said grooves and provided with an elongated slot of the same width throughout and extending into the main portion of the bracket member to permit the projecting head of the fastening member to freely pass into the slot and engage the end thereof whereby to limit the 120 displacement of the bracket member in the grooves when in position for use.

4. A detachable ventilating shade bracket comprising a plate adapted to be attached to a window-sash, and having overturned inwardly extending lugs on the top and bot- 130

tom edges thereof, terminating short of the ends to form grooves opening to the surface of the plate inwardly, said plate being provided with spaced openings adapted to receive headed fastening members, and a bracket member having one end disposed at an angle, said end adapted to be slid into said grooves and provided with an elongated slot extending into the main portion of the bracket in angular relation to the part engaged with the grooves for receiving the head of a fastening member, said fastening member constituting means for holding the

plate to the sash and positioning the bracket member with respect to the plate.

15

5. A shade bracket having an attaching portion for securing the same to a window-sash and having means at one extremity for receiving the end of a shade roller, a portion of the bracket adjacent the said extremity and spaced from the same having an offset bend extending outwardly to permit the edge of a shade to extend therein when raised and lowered.

In testimony whereof I affix my signature.
GEORGE ANDERSON.
